DRINK CONTAINER

Nell S. Fourqurean, 1701 E. 9th St.,
Hopkinsville, Ky. 42240
Filed Aug. 31, 1966, Ser. No. 576,362
5 Claims. (Cl. 215—1)

ABSTRACT OF THE DISCLOSURE

The unspillable container disclosed lends itself to practical use as a sick room aid and is made of glass or other acceptable material. It has a stable flat bottom, is self-standing and will rarely capsize. The upper portion embodies a nicely rounded shoulder merging into an upstanding filler neck provided with a disposable dust cap. An easy-to-hold handle is fixed on a vertical side of the container body. That portion of the shoulder directly above and aligned with the upper end of the handle is provided with an orifice which serves as an air vent but primarily serves to accommodate an insertable and removable straw or drinking tube. The drinking tube can vary in length depending on the needs of the patient and whether lying down or sitting up. A suitably graduated contents indicating scale is provided on one easily-viewable side. This unique container well serves the purposes for which it is adapted for use.

This invention relates to a new and improved sick room aid which is expressly designed and capably adapted for use at home, in nursing homes for invalids, hospitals, clinics, and the like and has to do, specifically classified, with a drinking glass which is uniquely constructed to better accommodate a currently usable type pliant bendable-type straw or a conventional angle-type rigid drinking tube.

An objective in the instant matter is to advance the art which pertains to appliances and accessories which are acceptably suitable for practical and reasonably safe use by an ill patient (a sick or handicapped child, a feeble or bed-ridden adult patient, as the case may be). More particularly, the objective is achieved, not by altering the straw or tube or the manner of use usually resorted to by the patient and nurse, but by providing a 45 structurally novel container or, as it is best known, a drinking glass.

Briefly, the drinking glass or container can be and preferably is made of non-breakable glass or plastic material and can be transparent and perhaps disposable, if desired. The experimental model has a flat bottom which is substantially three inches in diameter and is amply stable when seated on a support surface to minimize the likelihood of easy capsizing. Also, it is about four inches or so high and of appropriate cross-section to provide the capacity needed or desired. Then, too, a suitably graduated clearly visible measuring scale is provided on one side.

Keeping in mind that one of the significant aspects of the concept is to effectively assist and aid the patient and nurse or other attendant it is another purpose of the invention to promote ease and reliance of handling and, to this end, the body of the container, which defines the receptacle portion, is preferably exteriorly provided with an easy-to-hold handle or handgrip positioned much as it would be on a mug for self-evident handling needs.

A more important and resourceful aspect of the concept has to do with the shaping of the upper or top portion of the body and, with this in mind, it will be noted that this upper portion is concavo-convex to provide a nicely rounded shoulder found for example in bottle-type containers, and which merges into the centralized filler

2

opening at the top. For best results the filler opening is encompassed by an upstanding collar or neck which serves to permit the attachment thereto of a quick applicable and removable rim or flange on a dust cap or closure.

10 In addition to the handle and capped neck a feature of paramount importance has to do with the provision in the shoulder portion of an orifice or port which is usually circular and which permits the depending branch portion of the straw or drinking tube to be passed downwardly therethrough into the interior of the receptacle portion of the container. It will be noted that the orifice is of a size greater than the cross-section of the straw, functions as a vent, and is located between the neck and the upper end of the handle and in fact in alignment with the upper attached end of the handle or handgrip.

15 These together with other objects and advantages which will become subsequently apparent reside in the details of construction and operation as more fully hereinafter described and claimed, reference being had to the accompanying drawings forming a part thereof, wherein like numerals refer to like parts throughout, and in which:

20 FIG. 1 is a view in perspective of a drinking container constructed in accordance with the invention and showing the manner in which a glass or an equivalent drinking tube (pliant straw, if desired) is used.

25 And FIG. 2 is a view on a slightly enlarged scale taken on the plane of the section line 2—2 of FIG. 1.

30 As will be evident from the preceding description the device is broadly referred to as a container but is also known in the art and trade as a potable liquid containing and drinking glass for hospital and similar use. It actually resembles a relatively small jar in over-all external appearance. It is made of economical plastic material, perhaps even glass. In fact it is within the purview of the concept to make such a container of throw-away or disposable cardboard such as is used in manufacture of paraffin-coated milk and soft drink cartons. In any event it is preferably provided with a flat disk-like bottom 4 which is usually about three inches in diameter to render it reliably self-standing. The main part of the body is cylindrical as shown at 6. The upper or top portion of the body is concavo-convex and provides a nicely rounded shoulder portion 8. This shoulder portion is provided on one side with an orifice or equivalent port or opening 10 which is of a shape and diameter to permit ready insertion and removal of the column portion 12 of the attachable and detachable drinking tube 14. The mouth portion of the tube is denoted at 16 and the usual angular bend at 18. It will be understood in connection with this drinking tube that it is purely representative here in that the expression "tube" is intended to also comprehend the now popularly used pliant and bendable-type drinking straws, not shown. The upper or top portion of the container has a suitably enlarged filler opening as at 20 which is encompassed by a vertical upstanding endless collar or neck 22 which is also referred to in the art as a "filler" neck. This neck is amply rigid to accommodate the depending annular flange or rim 24 of the closing cap or lid 26. The lid proper is denoted at 28 and serves to span the opening and constitutes a satisfactory protector in that it closes the receptacle portion, prevents spilling and guards against the entrance of dust, insects or extraneous matter as is obvious.

35 40 45 50 55 60 65 70 75 80 85 90 95

The side wall 30 is provided with the aforementioned handle or handgrip. This grip comprises an arcuately bowed strap 32 having an upper end 34 superimposed on and affixed to the body and a similarly attached lower end portion 36. The handle or handgrip is vertically disposed, well balanced and is preferably located so that it is in line with the orifice 10.

In practice it is also within the purview of the invention to provide a measuring scale 38 having suitably arranged and clearly visible graduations 40.

It is evident that the orifice 10 supports and securely holds the drinking tube in its intended place and eliminates excessive moving or even the necessity of the patient or user holding the tube. In other words the tube stays put. The drinking tube can vary in length depending on the need of the individual whether lying down or sitting up. As stated the handle or handgrip is directly under and in line with the orifice 10 and the orifice 10 functions as an air vent. The top or lid 26 provides the sanitary feature desired and in addition minimizes the likelihood of spillage. Generally the top will be made of disposable material.

It is submitted that the invention well serves the purposes for which it is intended and that a more detailed description is unnecessary.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. For use in one's home, nursing homes for invalids, hospitals, clinics and the like, a liquid containing and drinking glass comprising a self-standing container having a bottom provided with an integral upstanding hollow body, said body having an upper part gradually decreased in diameter and merging with and terminating at an upper end in an open mouth encompassed by an integral filler neck, a readily applicable and removable lid providing a cover for said mouth, said lid being operatively but removably mounted on said neck, said decreased portion constituting and defining a shoulder, said shoulder being provided with a restricted orifice adapted to permit passage of and to retentively hold a patient's drinking straw or a feeding tube, said bottom being flat, said body being cylindrical in cross-section and transparent, said shoulder being concavo-convex, said body being exteriorly provided with a fixed handgrip, and said orifice being in alignment with said handgrip.

2. The drinking glass according to claim 1, and wherein said orifice is located in a plane below the plane of said filler neck and above the plane of the upper end of

said handgrip, said handgrip comprising a longitudinally bowed, easily grippable rigid strap member having upper and lower ends superimposed on and affixed to said body.

3. The drinking glass defined in and according to claim 1, and wherein said orifice is of a diameter slightly greater than the cross-section of said drinking straw, whereby to provide a vent when the straw is in use.

4. The drinking glass defined in and according to claim 2 and wherein said container is jar-shaped in over-all 10 appearance, said body being larger in diameter than the diameter of said mouth to minimize the likelihood of accidental capsizing when being used by an unaided patient, and also wherein said body is provided with a suitably calibrated measuring scale indicative of the capacity of 15 the receptacle portion of said container.

5. An unspillable liquid containing and drinking glass for use in one's home, nursing homes for invalids, hospitals, clinics and the like comprising a self-standing container having a bottom and an integral upstanding hollow body, said body having an upper part gradually decreased in diameter and merging with and terminating at an upper axial end portion in an open mouth encompassed by an integral filler neck, said decreased portion constituting a shoulder, said shoulder being provided with an orifice adapted to permit passage of and to retentively anchor and hold a significant portion of an insertable and removable drinking straw, said shoulder being concavo-convex, a handgrip fixed on a vertical side of the body of said container, said orifice being located in alignment with said handgrip in a plane below the plane of said filler neck and above the plane of a cooperating upper end portion of said handgrip, said handgrip comprising a longitudinally bowed, easily grippable strap member.
